UNITED STATES PATENT OFFICE.

BRYAN TYSON, OF WASHINGTON, DISTRICT OF COLUMBIA.

AMALGAMATOR AND CONCENTRATOR.

SPECIFICATION forming part of Letters Patent No. 270,156, dated January 2, 1883.

Application filed January 7, 1882. (No model.)

To all whom it may concern:

Be it known that I, BRYAN TYSON, a citizen of the United States, residing at Washington, in the District of Columbia, have invented certain new and useful Improvements in Amalgamators and Concentrators, of which the following is a specification, reference being had therein to the accompanying drawings.

My invention consists in certain improvements in amalgamators and concentrators, which will be fully understood by the following-described claims.

In the accompanying drawings, Figure 1 is a top view of my machine. Fig. 2 is a side view of the same. Fig. 3 is a front view. Fig. 4 is a section of the concentrator. Fig. 5 is a top view of the same. Figs. 6 and 7 are detached views. Fig. 8 is a cross-section of the grooved riffle, showing a plunger therein. Fig. 9 is a detached top view of the grooved riffle. Fig. 10 is a section showing the form of the grooved plate and skimmer. Fig. 11 is an end view of the corrugated plate. Fig. 12 is a detached section, showing the relation of the stationary and movable rings.

In the construction of my improved amalgamator and concentrator a suitable frame is made with three standards, A, B, and C, Fig. 3, for supporting the gearing, and two other standards, D and E, for supporting the concentrator. Upon said standards A, B, and C are mounted four horizontal shafts or axles, F, G, H, and I, Fig. 2, the first carrying the main driving-wheel J. The second carries crank-pinion K, and the third carries the pinion L and crank-wheel M, Fig. 3. The fourth shaft or horizontal axle, I, Fig. 3, is mounted on the two standards A and C, and carries the gear-wheel O and cams P and Q Q for operating the plunger or thin pointed blade R, as follows: One or more of the plungers R, according to the length of the grooved riffle to be operated upon, are to be made fast to the sliding frame S, and the same arrangement as to plungers is to be made for all the grooved riffles that it is desirable to use; but as a general thing four running parallel to each other and crossing the sluice at right angles is thought to be ample. By every revolution of the cams Q Q the sliding frame S will be raised, carrying with it the plungers R, which will be lowered gradually by means of the weight of the

frame S. The sand and sulphurets overlying the quicksilver in the grooved riffle, with which the riffle has previously been partially filled, will thus be prevented from packing. The larger cam, P, acting through the sliding lever N, operates the ratchet-wheel S', which has a crank, T, attached to connecting-rod U. A horizontal reciprocating motion is thus given the sliding frame S, which carries the plungers R, above described. The plungers are thus made to travel to and fro the entire length of the grooved riffle W, keeping the sands loose, and thus facilitating the taking of the precious metals. The ratchet-wheel S' is provided with a dog, V, to prevent the ratchet from recoil in connection with the crank action.

The grooved riffle W, with extension plates or flanges X and Y, Figs. 8 and 9, to right and left, can be constructed of some hard metal, and should be placed at right angles across a sluice-box or other device having a suitable grade, so as to cause the water and sands to flow freely over them. In addition to this grade or inclination of the grooved riffle W or the two plates X and Y, the projecting lip on plate Y is about one-half to three-fourths inch below the general surface-plane of plate X.

The groove W should be about one inch wide and at least one inch deep, and partially filled with quicksilver, the quicksilver working much better when in a considerable body.

The plate Y is brought to a sharp edge on the side situated upstream, the construction being such, in connection with the wall of grooved riffle, as to form a curve just below and including said edge. In the flow downstream the precious metals—such as gold and silver—being heavier, will strike below said edge, and the force of the water, in connection with the curve, will create a back under-current, recrossing the grooved riffle W, during which action the precious metals will lodge in the stratum of sand overlying the quicksilver, and the agitation given these sands by the plungers R will cause said metals to be precipitated onto the quicksilver, where it will either become amalgamated or lie there at rest. The curve below Y will also serve another good purpose, which is to catch and break the force of the water, and thus prevent the quicksilver from being washed out.

The plate Y can be made detachable and re-

versible, so that when the upper edge becomes worn the other can be turned upstream.

The sands and other heavy substances that strike beneath the sharp edge of Y, being thus deflected downward and backward, will have a tendency to choke and obstruct the grooved riffle W for lack of a proper outlet. To remedy this defect, we have triangular or wedge-shaped lugs Z Z Z, placed at appropriate distances on the top of plate X, the sharp ends upstream and the thick ends below or downstream. The lower stratum of sand that carries the precious metals will strike with considerable force beneath the sharp edge of Y, and by means of the curve beneath will be turned back and made to recross the grooved riffle W. The precious metals, will by reason of their greater weight, settle into the stratum of loose sand overlying the quicksilver, and will finally be brought into contact therewith. The direct flow of the main current downstream will have a tendency to pack and to hold down the portion of sand and water that has been deflected and turned back, as aforesaid. The function of the wedge-shaped lugs Z Z is to relieve this pressure by furnishing convenient places for outlet. There is no pressure immediately behind the downstream ends of said lugs, in consequence of the stream being divided by them. Consequently the water and sand that have been deflected, as aforesaid, will rush to these places where, by means of the pressure already described, they will be boiled out with considerable force. The sand thus boiled out is placed on the top or near the top of the flowing current and carried into the waste. Increased facilities are thus afforded for drawing the precious metals into the grooved riffle W, and for settling them to a place of safety after they have been drawn in; but owing to the weight and tenacious nature of black sand and sulphurets, one or both of which are generally present wherever gold is found, and the tendency of said substances to form a crust, the above-described device cannot be considered reliable for taking the precious metals, as said heavy substances frequently form a crust over the quicksilver in the grooved riffle W of sufficient firmness to prevent the precious metals from being brought into contact with the quicksilver. The plungers R, arranged and operated as already described, will prevent the formation of a crust by keeping said heavy substances constantly loose. The backward flow of water can thus much more readily take hold of heavy substances and cause them to be washed into the waste, and in this way prevent any inconvenient accumulation over the quicksilver. There will generally be a deposit of said heavy substances on top of the quicksilver in the grooved riffle W, particularly on the upstream side; but by keeping them loose by means of the plungers R their presence will not be detrimental to taking the precious metals.

In order to catch any waste quicksilver that may flow from works situated above the grooved riffle W and at the same time retain a uniform

quantity of quicksilver in said riffle, I use a crooked pipe, a, that passes through the end wall of grooved riffle into the quicksilver near the bottom, the mouth thereof being below the surface of the quicksilver, so that no sands nor other similar substances can get into the pipe. By turning the outer end of pipe the quicksilver can be adjusted to any desired quantity. Any surplus quicksilver that comes from above in consequence of wastage and being caught in the grooved riffle will cause a similar quantity to flow out at the end of the pipe, where it can be caught in some appropriate vessel.

This concludes a description of my device for taking such of the precious metals as will readily amalgamate with quicksilver; but a device to meet the requirements of the day must also be provided with suitable mechanism for taking sulphurets and other rebellious substances.

I will now proceed to a description of my device for taking sulphurets and other rebellious substances of value that will not readily amalgamate with quicksilver, nearly all which are lost when amalgamating works of the above-described character only are used. The following, therefore, is to take the substances of value that have passed the device above described, and thus, between the two, to materially lessen the loss that has heretofore generally occurred.

In order to work the pulp economically and at the same time save a larger percentage of the substances of value, I first, by means of an appropriate device, throw a large percentage of the valueless portion of the material into the waste. To effect this object, the pulp, after running for a suitable distance down a properly-constructed sluice-box, passes over the corrugated plate e, Figs. 1, 10, and 11. The ridges on said plate should be brought to a sharp edge at the top. They will extend up into the pulp, thus increasing the friction at the bottom, and consequently decreasing the momentum of the heavier and more valuable substances, which will settle into the grooves between said ridges. The effect of the ridges and grooves will be to cause the skimmer d to take out a larger percentage of the substances of value and a smaller percentage of the valueless portion of the material, thus procuring a better concentration than can be done if a plain smooth plate be used. The skimmer d is adjustable and reversible. After the top edge becomes worn the corresponding one at the bottom can be turned up. It should be made of some suitable hard metal, in order that the front edge may be kept sharp and in good condition. As there is considerable fall after leaving d, the water here forms a curve, and thus gives a bearing-down tendency to the bottom stratum of pulp that is projected against the sharp edge of the skimmer d. All heavy substances of value, being at the bottom, will, by means of the skimmer d, be precipitated through the opening e into the space below, from whence they are conducted into the concentrator. The

skimmer *d* should stand a little higher than the bottoms of the grooves in the corrugated plate *c*. After the skimmer *d* becomes worn it can be transferred to render service as plate *f*.

5. Where the flow of pulp is large a series of concentrating devices composed of the corrugated plate *c* and skimmer *d* can be used until the volume is reduced to a proper size to be worked by one concentrator.

10. Having procured as high a concentration as it is possible for me to do without machinery, my next step will be to procure, by the aid of machinery, clean sulphurets or other substances of value ready for the reduction-works.

15. The concentrations, after dropping through the space *e*, are washed through the pipe *g* and deposited in the concentrator *h*, Figs. 1 and 3. This pipe may be branched and extended around the rim of the concentrator-pan *h*, so as to discharge at four or more points, and thus more evenly distribute the materials to be agitated and separated or concentrated.

20. The concentrator consists of a pan, *h*, having the bottom thereof lower at the periphery than toward the center. Said pan is provided with or supported on a vertical shaft, *i*, having a reciprocating partial revolution by means of connecting-rod *j*, operated by crank-pinion *k*, and of a novel arrangement of agitators 25 and other devices that will now be described.

30. Supported by the circular frame *K*, which in turn rests on and is supported by a convenient number of standards or posts, *h'*, are a series of rings, *l*, fastened to the removable cross-bars *m*, Figs. 5 and 12. Below these stationary rings are two annular agitators, *n* and *o*, Figs. 4 and 12, having flanges or rims that extend up even with the tops of the stationary rings *l*. These agitators *n* and *o* are swung from

40. the plate *p* by the rods *q* *r*, and receive a partial rotary motion back and forth by means of the connecting-rod *S''* and crank-wheel *M*, Figs. 1 and 3. The annular plates or agitators *n* and *o* are provided with triangular lugs *t*,

45. Fig. 7, on their under sides for the purpose of greater agitation, and these lugs may be arranged to move the sand either from the center or toward the center, or both, as may be deemed best in practice. The edges of these plates

50. may be notched, as shown at Fig. 7, so as to work the sulphurets or other valuable substances to the place of discharge, and thus prevent overflow and wastage of said substances. The plate *p* rides on small rollers *u*, supported by a ring, *v*, on the removable cross-bars *m*. The bottoms of the stationary rings *l* are also provided with triangular lugs *w*, Fig. 7, so as to work the sand to or from the center, as may be desired.

55. The concentrator or pan *h*, Figs. 2 and 3, and annular plates *n o* are to be operated in opposite directions or both in the same direction, as may be deemed best.

60. The annular plates *n o* may be dispensed with, except the rims or flanges thereof; or rings similar to *l* may take the places of the flanges, and, as thus arranged, each alternate

ring may be agitated in the same way that the annular plates *n o* now are; or I can use one annular plate and one or more agitators of similar construction to *l*, as may be found best in practice.

65. The concentrator or pan *h* is provided with an automatic discharge for sulphurets or other substances of value, as follows: The pan *h* is provided with a bracket, *i'*, of proper dimensions for the support of the bearings *j'* and *k'* and other necessary accompanying fixtures. Said bearings support the pinion *y* and scraper *c*, the latter by a movement to and fro causing the concentrations to be discharged through the opening *l'*, Fig. 6. A ratchet-bar, *x*, Figs. 2 and 3, gears into a pinion, *y*, the shaft of which has a spiral groove, *a'*, with a lug, *b'*, fitting therein. The pinion-shaft, with scraper or raker *c*, travels to and fro longitudinally while the concentrator or pan is being shaken. The pinion itself travels laterally under the ratchet-bar. The lug *b'* being adjustable, the pinion-shaft can be regulated so as to discharge 85 any desired quantity. The bottom of the concentrator or pan being lowest at the circumference, Figs. 4 and 12, and the automatic discharge working a short distance from the bottom, quicksilver may be placed in the pan when, in addition to being a concentrator, it will also become an amalgamator.

70. In order to retain the pulp longer in the concentrator or pan, and thus increase the facilities for settling and saving the substances of value, I form zigzag courses or ways, *d'*, Fig. 5, to be traversed by the water containing the pulp. These courses or ways are formed by plates *e f g*, which are to be made fast to the stationary bars *l*. Said plates must 75 be of sufficient depth to prevent the water and pulp from flowing over the tops thereof. I claim to work with or without these plates, as may be deemed best in practice. When used the stationary wings *l* will require more grade 80 than usual in order to cause an even and regular flow of water and pulp through the zigzag courses aforesaid. When used in connection with eight courses or ways, as set forth at Fig. 5, it may be found advisable to admit the pulp 85 to the pan at eight points, so that each of the eight sluices will be dropped about midway the plates *f' g'*. The water and pulp will then have to pass to the right and left before entering the zigzag courses or ways *d'*. The pulp 90 will thence traverse said course to the place of discharge at *h'*, which is an open or bottomless space or other convenient arrangement for discharge.

95. Having described my invention, what I claim is—

1. The combination, with the sluice-box provided with the riffle *W*, of plungers *R*, sliding frame *S*; shaft *I*, provided with cams *P Q Q'*, crank *T*, and pitman connecting the frame *S* 105 with said crank, the ratchet-wheel *S'*, and devices connecting the same with cam *P*, substantially as and for the purposes described.

2. The grooved riffle *W*, provided with tri-

angular lugs Z, and having a reversible plate, Y, provided with a curved projecting lip, as described, whereby the under-current is turned backward to bubble up at the heels of said lugs, substantially as and for the purposes set forth.

3. The sluice-box provided with the transverse passage e, and having the grooved plate c on the upper side of said passage and the skimmer d on the opposite side of the passage, substantially as and for the purposes described.

4. The annular agitators n o, plate p, and devices connecting the two, as described, stationary rings l l, and means for supporting the same, in combination with the concentrating-pan h and devices for oscillating the said agitators n o and pan h, substantially as set forth.

5. The annular agitators n o, plate p, and devices connecting the same, as described, in combination with the concentrating-pan h and devices for oscillating the said agitators n o, and wheel K, provided with a crank and

connecting-rod for oscillating the pan h, substantially as set forth.

6. The stationary rings l l, secured to the cross-bars M, in combination with the concentrating-pan h, crank-wheel K, and connecting-rod j, substantially as and for the purposes described.

7. The pan h, provided with a bracket, i', and aperture l', in combination with the shaft provided with the scraper c, and devices for reciprocating said shaft, substantially as described.

8. The plates e' f' g', in combination with the annular agitators n o, stationary rings l l, and concentrating-pan h, substantially as and for the purposes described.

In testimony whereof I affix my signature in presence of two witnesses.

BRYAN TYSON.
